UNITED STATES PATENT OFFICE.

GEORGE N. MASON, OF READING, PENNSYLVANIA, ASSIGNOR TO READING HARDWARE COMPANY, OF READING, PENNSYLVANIA, A CORPORATION OF PENNSYLVANIA.

STORE-DOOR LATCH.

1,048,845.

Specification of Letters Patent.

Patented Dec. 31, 1912.

Application filed February 29, 1912. Serial No. 680,655.

To all whom it may concern:

Be it known that I, GEORGE N. MASON, citizen of the United States, residing at Reading, in the county of Berks and State 5 of Pennsylvania, have invented certain new and useful Improvements in Store-Door Latches, of which the following is a specification.

This invention relates to improvements 10 in store door latches, and the object in the present invention is to provide a latch in which a thumb lever is used as the means for withdrawing the latch bolt, with a simple means for locking it against opening 15 from the outside by means other than a key. In latches of this character it has been customary to provide thumb stops on the face of the lock case, by means of which the latch could be set for operation or locked 20 against such operation. In my present invention I do not employ such means, but while my latch is operable by thumb lever from either side of the door, it may be locked by key from the inside so that it 25 may be opened from the outside by key only, although the operation by thumb lever from the inside is not interfered with.

The invention consists in providing a slide- 30 able member, operable by the inside key cylinder, that will be placed in the path of the vertical latch operating member that is in connection with the outside thumb lever, so that this slide is either free to move or not, depending on the location of the 35 slide member operated by the key cylinder.

A further object is to provide means for 40 operating the latch bolt from the outside through the key cylinder, which I accom- plish by placing on the slide member a pivoted member that will be brought into 45 the path of the cam on the outside cylinder when the slide member has been moved to the position where the outside thumb lever action is stopped so that at the 50 same time that the thumb lever operation is prevented, the key operation is substituted.

The invention is more fully described in 55 the following specification and clearly illus- trated in the accompanying drawing, in which:—

Figure 1 is a plan view of the lock with the cover plate of the casing removed, showing the latch bolt projected and the parts in 55 position for operation either by key or

thumb lever from outside or inside. Fig. 2 is a like view, with the bolt retracted, the inside key cylinder having made an entire revolution, and the outside thumb slide locked against movement. Fig. 3 is a like 60 view, showing that the bolt has been retracted by the inside thumb lever. Fig. 4 is a sectional view on line 4—4 of Fig. 1.

The numeral 1 designates the casing, 2 a spring backed latch bolt, 3 the outside 65 key cylinder and 4 the inside key cylinder.

5 designates a slide, capable of operation by the cam 6 on the inside cylinder. This slide travels in guides in the casing as usual and is provided with the usual tumbler 7 70 for engagement with the cam 6. This slide 5 is also provided with a pivoted lever 8 which is carried along with the slide, and this lever has a dog 9 formed on its free end. This dog, when the slide has been moved to 75 the right, is placed in the path of the cam 20 on the outside cylinder. The slide 5 is also provided with a depending leg 10 formed with a foot 11, which foot is adapt- 80 ed to be moved into the path of the vertical slide operated by an outside thumb lever, to be described.

The latch bolt is provided with a flange 12 on its inner end and this flange is en- gaged by a lug 13 on the lower end of a 85 pivotally mounted three-arm lever 14. This lever is formed with an arm 14 in engage- ment with the latch bolt, as just described; with a second arm 15 in engagement with the dog 9 and a third arm 16 to which is piv- 90 oted a link, the opposite end of which is piv- oted to the free end of a bar 17 whose oppo- site end is pivoted in the casing and which bar crosses the path of a pair of vertical slides 18 and 19. These slides are capable 95 of being moved vertically by a thumb lever of any construction (not shown) such as are used on latches of this class, the slide 18 be- ing operable by the outside lever and the slide 19 by the inside lever. When either 100 lever is operated, the slide in moving up will raise the bar 17 and turn the three-arm lever 14 on its pivotal point, and retract the latch bolt. The latch bolt is also operable by the key cylinder on the outside, for the rea- 105 son that the cam thereon will contact with the dog 9 and through it depress the arm 15 of the pivoted lever, thus retracting the latch bolt by the turning of this lever. This ac- tion of the lever, by the outside key, is only 110

possible however when the slide 5 has been moved by the inside key to the position where the dog is brought into the path of the cam on the outside cylinder.

- 5 When the slide 5 is moved as just described, it will carry the leg 10 with it and the foot 11 thereon will move to the position immediately over the vertical slide 18, which is connected to the outside lever, thus effectually locking the slide and incidentally the latch against movement by the outside thumb lever; this action of locking it against movement by the thumb lever from the outside, does, as above stated, place the parts in 15 position for being operated from the outside through the action of the key cylinder.

It is evident that the latch is operated as usual, through a thumb lever, from either side, but, when it is desired to lock the latch 20 against action from the outside by others than those provided with keys, the inside key cylinder is operated, thus placing the parts in position where they can be operated from the outside, by a key only, the thumb lever action being stopped.

By this construction, accidental interference with the latch is impossible, for the reason that it is necessary to deliberately set it for the action desired, and this can be done 25 only through the inside key cylinder.

Having thus fully described my invention, what I claim is:—

1. In a store door latch the combination of a casing; a spring backed latch bolt; a 35 three-armed lever operably connected to the latch bolt; means for turning the lever to retract the latch bolt comprising a pair of vertically movable slides; a slidable locking member; a leg on said member adapted to lock one of said slides; a dog on said slidable member adapted to move the three-armed lever; an inside key cylinder for operating the slidable locking member and an outside

key cylinder for operating the three-armed lever through the dog.

45

2. In a latch for doors, a casing; a latch bolt; a three-arm lever in operative connection with the bolt; means for moving said lever from either side of the door, comprising a pair of vertically movable slides, a 50 pivoted bar and a link connecting the bar and the lever; a locking slide adapted to lock the outside operating vertical slide against movement; means on the slide for operating the three-arm lever when the said slide is in 55 locked position; an inside key cylinder for operating the locking slide and an outside key cylinder for actuating said dog.

3. In a door latch a casing; a latch bolt; a lever for retracting the bolt; means including vertical slides for operating the lever from either side; key operated locking means for one of said slides; and outside key operated means for operating the lever when said slide is locked against movement.

65

4. In a latch, a casing; a bolt; means for retracting the bolt from both sides; means within the casing for locking the outside retracting means; and a supplemental, key-operated bolt retracting means, operable 70 only when the outside retracting means is in locked position.

5. In a latch a casing; a latch bolt; an operating lever therefor; inside and outside operated slides for turning said lever; inside key operated locking means for the outside operated slide and outside key operated means for turning said lever when the outside operated slide is locked.

75

In testimony whereof I affix my signature 80 in presence of two witnesses.

GEORGE N. MASON.
